HEIGHT GAGE

Thomas L. Telford, 1024 E. 5th St., Royal Oak, Mich.

Filed Nov. 20, 1961, Ser. No. 67,605

Term of patent 14 years

(Cl. D52—6)

FIG. 1 is a front elevational view of a height gage embodying my new design.

FIG. 2 is a side elevational view thereof.

FIG. 3 is a top plan view thereof; and

FIG. 4 is a bottom plan view thereof.

The undisclosed side of the gage is substantially like the side shown except for the presence of the handle, and the rear is substantially plain in appearance as indicated in FIGS. 2 and 3.

I claim:

The ornamental design for a height gage as shown.
